PRESTON E. GILLING, OF HADDON HEIGHTS, NEW JERSEY, ASSIGNOR TO RADIO
CONDENSER COMPANY, OF CAMDEN, NEW JERSEY

ELECTRICAL CONDENSER

Application filed February 27, 1929. Serial No. 343,196.

This invention relates to improvements in the design of an electrical condenser of the variable type such as are used in radio receiving circuits. In radio receiving sets it has become quite customary to use a plurality of condensers which tune the various stages by a single control, and where condensers are so operated, it is very important that each tuned circuit be at the maximum point of resonance 10 for the stations which it is desired to tune in.

Due to the variations in the manufacture of tuning condensers and the variations which occur in the coils used in the tunable circuits, and further due to the location of the 15 various pieces of apparatus in the receiving set, there must be some means of adjusting each condenser so as to change its initial capacity curve sufficiently to bring all of the tunable circuits to the maximum point of 20 their resonance curves at any setting of the unit control device.

In the past, various compensating means have been proposed and it is the object of my present invention to provide a compensating 25 means that is much simpler than the arrangements heretofore proposed of which I am aware. In attaining the principal object, other ancillary objects will be apparent from a study of the specification taken in connection with the annexed drawings, wherein

Figure 1 is a side elevation of a single unit condenser to which I have applied my improvement, the rotor of the condenser being in fully exposed position or out of engagement with the stator.

Figure 2 is a side view taken from the left of Figure 1.

Figure 3 is a view taken on the line 3—3 of Figure 2.

Figure 4 shows a plate to carry the compensating adjusting screw and which may be used with the condenser shown.

In the drawings, 1 is the base of a condenser having bearing supports 2 and 3 extending therefrom. The bearing supports 2 and 3

carry a shaft 4 on which is supported a sleeve 5 carrying a group of spaced rotor plates 6. Preferably, one of the free ends of the rotor plates is anchored together by a tie bar 7. The outer rotor plate 8 has a segment 9 cut along the line 10 for the major portion of the periphery of the segment which it will be seen comprises the greater portion of the area of the plate 8. By leaving the segment 9 anchored to the plate 8, as indicated, between the points 11 and 12, the segment 9 can be moved back and forth by suitable actuating means, and this means is provided in the shape of an arm 13 carried on the rotor sleeve 5.

The arm 13 has a clearance hole therethrough to receive a screw 14 which is threaded into the segment 9 so that the segment may be changed in position with respect to the rest of the plate 8 from which the segment 9 is formed.

Cooperating with the group of rotor plates 6, is a group of stator plates 15 that are anchored to tie bars 16 and 17 disposed at opposite ends of the stator plates. These tie bars 16 and 17 are fastened to insulators 18 and 19 in any satisfactory manner as by screws 20, the insulators 18 and 19 being fastened to frame 1 in any satisfactory manner as by screws 21. Electrical contact is made to the stator plates by terminal 22 carried beneath the head of one of the screws 20 that engages one of the tie bars. In the form of condenser shown, the stator group of plates has an additional intermediate tie bar 23.

I can apply my compensating idea to the stator as well as the rotor, and this is indicated by Figures 2 and 3, wherein a segment 24 is cut from the outer stator plate 15 in a manner similar to the segment 9 on the rotor plate 8. As shown in Figure 3, the tie bar 23 may be long enough so that its end 25 can be bent upward and the adjusting screw 26

14' mounted in the upper end of the bent portion 25.

As an alternative arrangement, the tie bar 17 may be extended and similarly bent so as to carry the adjusting screw for the segment 24.

As a further alternative arrangement, instead of using either of the tie bars 17 or 23, a plate 27 may be mounted immediately adjacent the outer stator plate 15 and connected to the tie bars 16 and 17. As shown in Figure 4, a hole 28 is used to receive the screw 14 for actuating the segment 24. Either or both of the arrangements may be used in the same condenser, and while I have shown in this application, a single condenser which may be connected to another for multiple operation, the improvement may also be applied to condensers arranged in tandem in a single frame for unit control.

From what has been said, it will be observed that I have provided a very simple and inexpensive form of compensating means which specific arrangement is claimed herein.

Having thus described my invention, what I claim is:

1. In an electrical condenser including a stator and a rotor, each composed of a group of plates spaced for interleaving relationship as the rotor is operated, and means for altering the capacity curve of the condenser, said means comprising a single segment forming part of and cut from the outer plate of one of said groups with means for positively adjusting the position of the segment.

2. In an electrical condenser including a stator and a rotor, each composed of a group of plates spaced for interleaving relationship as the rotor is operated, and means for altering the capacity curve of the condenser, said means comprising a single segment forming the greater part of and cut for the greater part of its periphery from the outer plate of one of said groups with means for positively adjusting the position of the segment.

3. In an electrical condenser including a stator and a rotor, each composed of a group of plates spaced for interleaving relationship as the rotor is operated, at least the outer plate of one of said groups having a single segment comprising the major part of its area cut from the said plate, the cut extending for the major part of the periphery of the segment, and positive means for adjusting the position of the segment with respect to the balance of the plate.

4. In an electrical condenser including a stator and a rotor, each composed of a group of plates spaced for interleaving relationship as the rotor is operated, at least the stator group of plates being tied together by tie bars and at least the outer plate of one of said groups having a single segment comprising the major part of its area cut from said plate, the cut extending for the major part of the periphery of the segment, and a screw carried

by one of said tie bars for adjusting the position of said segment with respect to the fixed part of the plate.

5. In an electrical condenser comprising a fixed group of plate elements and a movable group of plate elements, and a single segment cut for nearly all its periphery from the outer plate of one of said groups, and a single positive means forming part of said group for adjusting the position of said segment. 70 75

In testimony whereof, I affix my signature.
PRESTON E. GILLING.
